UNITED STATES PATENT OFFICE

2,001,473

DOUBLE WALL STRUCTURE

Wallace W. Smith, Chicago, Ill., assignor to Inland Steel Company, Chicago, Ill., a corporation of Delaware

Application January 29, 1934, Serial No. 708,904

10 Claims. (Cl. 61—34)

My invention relates generally to structures, more especially piling structures, formed of spaced apart walls with interposed filling, and particularly to such structures of the cellular type each 5 wall of which is formed of a series of outwardly bowed arcuate sections, the invention having utility not only in temporary structures, such as for example cofferdams, but also in permanent structures, such as for example sea walls or 10 breakwaters, or retaining walls to form docks or hold back the shore line against the action of waves.

Structures of the kind above referred to require at intervals along their spaced apart walls, 15 cross-wise extending tension elements for preventing undue outward distortion of the walls by the pressure against them of the filling, such as sand or dirt, commonly filled into the space between the walls.

Such tension elements as heretofore commonly provided comprise sheet piling driven to place and presenting a series of solid partitions between, and connected with, the spaced apart walls, but such structures present the objection that 25 they are expensive constructions, expensive to install and require the filling to be applied to both sides of the tension elements before completing the filling of either compartment, or cell of which it forms a wall.

My object is to provide a structure of the double wall cellular arcuate-section type which shall 30 present the advantages of such structures as hitherto provided without their objections; may be constructed and installed relatively economically; shall not require the use of divers and shall afford communication between adjacent compartments or cells thereby permitting of the dumping of the filling into the space between the walls by progressively full-filling adjacent compartments or cells, as distinguished from a filling 35 procedure involving the successive partial filling of adjacent compartments or cells before either may be completely filled.

Referring to the accompanying drawings:

Figure 1 is an enlarged plan view of one of the 40 similar ends of a cofferdam embodying my invention.

Figure 2 is an enlarged broken plan view of a portion of the structure shown in Fig. 1.

Figure 3 is an enlarged plan view illustrating the construction at each portion of the structure thereof equipped with a tension-frame structure in accordance with my invention.

Figure 4 is a face view of the upper end of one

of the similar sheet metal piles of which the wall structure of the cofferdam is built.

Figure 5 is an enlarged section taken at the line 5—5 on Fig. 1 and viewed in the direction of the arrows.

Figure 6 is an enlarged broken sectional view taken at the line 6 on Fig. 5 and viewed in the direction of the arrow.

Figure 7 is a view like Fig. 1 of a modification of the wall structure of the preceding figures.

Figure 8 is an enlarged broken plan view showing the construction at each of the tension frames connecting the walls of the structure of Fig. 7.

Figure 9 is a broken plan view of the end of the structure shown in Fig. 7.

Figure 10 is an enlarged section taken at the line 10—10 on Fig. 7 and viewed in the direction of the arrows.

Figure 11 is a face view of one of the similar frames forming parts of the walls of the structure of Fig. 7.

Figure 12 is an enlarged plan view showing a modification of the structure shown in Figs. 8 to 11, inclusive.

Figure 13 is a face view of a modification of the tension element of the structures shown in Figs. 1 to 11, inclusive.

Figure 14 is an enlarged sectional view of the tension element of Fig. 13, the section being taken at the line 14—14 on Fig. 13 and viewed in the direction of the arrows.

Figure 15 is an enlarged plan view showing a detail of the construction common to the structures shown in Figs. 1 to 11, inclusive.

Figure 16 is a view like Fig. 5 of a modification of the structure of the preceding figures.

Figure 17 is a broken plan view of a portion of the structure of Fig. 16; and

Figure 18, a broken view in side elevation of the portion of the structure shown in Fig. 17.

Referring to Figs. 1 to 6, inclusive, 21 represents one of the similar shore-ends of a bow-shaped cofferdam installed in place adjacent the shore line of a body of water, as for example a river, and extending from the shore line into the water 45 and embracing the area from which the water is to be excluded, as for example for the building of a bridge abutment.

The cofferdam is shown as formed of inner and outer walls 22 and 23, respectively, extending continuously along the length of that part of the structure which is submerged and each formed of edge-interlocking sheet metal piling sections driven into the ground and tied together at intervals as hereinafter described to restrict 50 55

the outward deformation of the walls under the pressure of filling, such as sand, dirt, or other suitable material, filled into the space between these walls, as for example to the elevation indicated at 24.

5 The piling sections forming the walls 22 and 23 are placed and driven in such arrangement as shown as to cause each wall throughout its length to comprise a series of outwardly bowed arcuate sections, the adjacent ends of which are connected with the means hereinafter described for tying the walls 22 and 23 together at intervals.

10 At the ends of the cofferdam the inner and outer walls 22 and 23 may be connected together as shown to render these walls continuous as shown in Fig. 1 and each end of the wall structure thus provided connects with a single wall 25, shown as of sheet piling, which is carried up onto the shore and driven into the ground to prevent flow of water around the ends of the cofferdam and into the area to be rendered free 15 of water.

15 Any suitable form of sheet metal piling may be used for the main portions of the walls 22 and 23 that shown being of a common type as represented at 26 having at its vertical edges, thumb and finger projections 27 and 28, respectively, which permit the piling sections to be connected together to form a wall structure by sliding one section upon the other at the projections referred to, the sections becoming interlocked to prevent lateral separation.

20 The piling sections at the extreme ends of the double wall structure of the cofferdam and which extend adjacent the outer edges of the single wall portions 25 represented at 29 of the end shown in Fig. 1, are of general Y-shape in cross section presenting three flanges 30, 31 and 32. The outer edges of the flanges 30, 31 and 32 have thumb and finger projections as in the case of the piling sections 26 the sections 29 slidingly interlocking at the projections on their flanges 30 and 31 with the projections on the adjacent ones of the piling sections 26 and at the projections on their flanges 32 with the adjacent thumb and finger projections on the walls 25.

25 The walls 22 and 23 are connected together at the ends of their arcuate sections by transversely disposed tension means hereinafter described, the sheet piling sections of these walls at the location of the tension means and represented at 33 being shown as of a construction different from the sections 26 in that they are of general Y-shape in cross section the head portions 34 of which, and provided with thumb and finger projections 35 and 36 as in the case of the other piling sections, being interlockingly connected with the adjacent edges of the wall sections formed of the piling sections 26 and thus constituting portions of these walls. The outer edge of the other portion 37 of each of the piling sections 33 is also provided with thumb and finger projections 38 and 39, respectively.

30 While the piling sections 33 may be of any desirable construction they are shown of a form in which the portions 34 and 37 are provided as separate sections connected together by plates 34^a and 34^b of angle shape in cross section.

35 The tension means above referred to are shown as in the form of openwork frames each comprising upright bars 40 at the ends of the frame the outer vertical edges of which are provided with thumb and finger projections 41 and 42, respectively, adapted to be assembled with the piling sec-

tions 33 by sliding them at their thumb and finger projections along the thumb and finger projections on the portions 37 of these piling sections with which the bars 40 become interlockingly engaged to prevent relative lateral movement.

40 Each frame also comprises upper, lower and intermediate pairs 43, 44 and 45, respectively, of angle irons, which are rigidly connected at their ends with the uprights 40, the structure thus provided preferably being trussed by the bars represented at 46 and secured to the several pairs of angle irons. At the lower ends of the uprights 40 are angle iron sections 47 which form shoes at which the frames may rest on the earth beneath them.

45 In the particular construction shown tie rods 48 each formed of sections connected together by a turn buckle 49 and extending from one wall to the other are provided at intervals along the cofferdam in substantially vertical alignment with the tension frames referred to. A desirable way of connecting the tension rods 48 to the walls 22 and 23 is shown more clearly in Fig. 15 wherein the ends of the rods 48 extend through the holes in the upper portion of the sections 34 and in the adjacent parts of the angle iron 34^a.

50 Where the height of the walls is such that a single one of the crosswise extending tension frames of a size within commercial expediency, is not sufficient to form the sole tying means between the walls, tie rods such as those above referred to and shown at 48 would be provided as above described, and where the walls are especially deep a plurality of the frames placed edge-wise one upon the other, with a tie rod 48 above the upper one if necessary, would be employed.

55 In the building of the cofferdam the part of one of the walls 22 and 23 up to and including one of the sections 33 is built by driving the piling sections 26 forming it, preferably before the opposite section 33 of the other wall, and possibly in some cases before the adjacent terminal one of the sections 26 of this other wall, is driven. One of the tension frames is then lowered on the driven section 33, the adjacent thumb and finger projections at one edge of the frame sliding into interfitting relation to the similar projections on this section 33 as shown. The opposing portion of such other wall is then completed by alining the piling section 33 at certain of the thumb and finger projections thereon with the projections on the terminal one of the sections 26 and with the projections on the adjacent outer end of the tension frame and, in case the terminal one of the sections 26 has not been driven, the same alined at the thumb and finger projections on its remote edge with the thumb and finger projections on the next to the last one of the sections 26, and such of these sections as not yet installed, driven to place.

60 The assembling of the tension frame with one portion of one wall before the opposed portion of the other wall has been built up to, or near, the point at which the tension frame is to be connected therewith, and the completion thereafter of this other opposed wall portion is of great practical advantage as it enables proper connection to be made between the outer swinging end of the frame and the adjacent last finished wall portion regardless of variations in the location of the terminal one of the piling sections 26, this being possible because of the adjustability of the frame for the swinging movement and the fact that the section 33, as also the sections 26, have the capacity of interlocking with the adjacent 65 70 75

piling sections and the tension frame, in various positions of the frame relative to the end ones of the series of piling sections 26 of this last finished opposed wall portion.

5 Referring to Figs. 7-11, inclusive, the construction therein shown is the same as that disclosed in the preceding figures except as to the construction of the spaced apart walls of the cofferdam which, in this case, are composed of 10 piling sections, as for example of wood, and a backing structure therefor comprising backing frames and connecting piling sections therefor to which the tension frames are connected.

15 The piling sections of this particular construction and forming the walls of the cofferdam and represented at 50 and 51, are indicated at 52, these piling sections being driven to place as in the case of the piling sections of the construction of the preceding figures.

20 The backing frames for the piling sections 52 are represented at 53 and are positioned against the outer faces of the groups of piling sections 52 to which the latter are connected in any suitable way.

25 Each frame 53 is shown as comprising upright end bars 54, a vertical series of substantially horizontal angle irons 55 connected at their ends with the bars 54 and truss bars 56 connected with the angle irons 55 for trussing the frame, the terminal edges of the bars 54 being inturned as represented at 57 and terminating in thumb and finger interlocking projections as described of the slidably interlocking parts of the construction of the preceding figures.

30 The piling sections 52 of each wall 50 and 51 are spaced apart at intervals as shown adjacent the ends of the frames 53 and the wall rendered continuous at these spaces by the bars 54 of the frames and by bars 58 of the same construction

35 as the bars 53 which are slidably interlocked with the edges of the bars 54 as shown and similarly interlocked with the ends of the tension frames represented at 59 and shown as of the same construction as the tension frames of Figs. 1 to 6 and arranged at intervals along the walls and extending crosswise thereof.

40 The single walls of piling at the terminals of the cofferdam and represented of the one end thereof at 60, are of the same construction as the walls 25, being connected with the ends of the body of the cofferdam by metal piling sections 61 which complete the closure of these ends and are of the same construction as the corresponding piling sections 29 of the preceding figures.

45 The manner of building the cofferdam of this particular construction is similar to that of the preceding figures, the backing frames 53 being first lowered into place and the sections of the wall formed of the piling sections 52 which they are to back, then driven to place, the adaptability of the tension frames 59 for swinging movement and the provision of the Y-bars, permitting of the ready joining of the swingable ends of the tension frames with the adjacent wall structure as explained of the construction of the preceding figures.

50 In the modification shown in Fig. 12 the frames 53 instead of being directly connected at their bar portions 57 with the piling section 50 as in the case of the construction shown in Figs. 7 to 11, inclusive, are connected thereto by means of interposed piling sections 62 shown as of the same form as the piling sections 26 and slidably interlocked at their edges with the bar portions 57 and the piling section 58.

55 Figures 13 and 14 illustrate a modification of the tension frame represented at 43 in Fig. 5. The frame of Figs. 13 and 14 comprises uprights 63 at its ends and of the same construction as the uprights 40, connected together by upper and lower pairs 64 and 65, respectively, of angle irons and intermediate angle irons 66, 67, 68 and 69 located at opposite sides of the uprights 63 and disposed in staggered arrangement as shown, the frame structure thus provided being shown as 10 braced by tension bars 70 located between the bars of the pairs 64 and 65 thereof and between the intermediate bars 66-69, the bars 70, if desired, being welded to these intermediate bars.

15 The lower ends of the uprights 63 preferably of widened form, as represented at 63a, extend downwardly below the lower bar 65, and in the installing of this particular frame these depending portions 63a are driven into the ground whereby should the ground at the outer faces 20 of the wall become displaced, as by scouring, the stresses exerted by the fill, will be carried by these depending portions 63a to the frame of which they are a part, the lower bar 65 of which would extend against, or close to the ground, and 25 in such position cooperate, to the best advantage, with the depending portions 63a, in resisting stresses.

30 Figures 16, 17 and 18 illustrate a construction of cofferdam involving a modification of the tension elements connecting together the spaced apart piling walls at intervals. In this construction instead of providing these elements as rigid frames as described of the constructions of the preceding figures, they are provided in the form 35 of rods either stiff, or flexible as in the case of cables, extending from one wall to the other and located at points along the wall as described of the frames 43.

35 The spaced apart walls formed of piling sections are represented at 71 and 72 and the tension elements, shown as cables, at 73, these cables being shown as extending diagonally upward from the opposed walls 71 and 72 and in intersecting relation.

40 In this particular construction instead of providing bars of either the form of bars 33 or 58 as of the construction of the preceding figures of the drawings, the bars represented at 74 are provided these bars being shown as of general V- 45 shape having thumb and finger projections along their outer edges which slidably interlock with the piling sections forming the major portion of the walls 71 and 72, and at intervals along their length are provided with brackets 75 at which 50 the ends of the tension elements 73 are connected through the medium of pins 76 extending through these brackets. Preferably above, and in vertical alignment with, each group of tension elements 73, is a tension rod represented at 77 and corresponding with the tension rod 48.

55 In the building of the structure shown the tension elements 73 would preferably be connected at their lower ends with the bars 74 before these bars have been driven to place so that the connections just referred to may be made without requiring the service of a diver, and the other ends of these elements in upwardly extending position temporarily supported in any suitable way until the bars 74 have been finally driven to 70 place, whereupon they are connected at their upper ends to the bars 74 as for example in the position shown in Fig. 16 and thus in such positions that the services of a diver are not required, the lower ends of the elements 73 being 75

shown as pivotally connected with the bracket 15 adapting them to be swung upon the bars 14 to the positions referred to.

While I have illustrated and described certain particular constructions constituting embodiments of my invention, I do not wish to be understood as intending to limit it thereto as the structures shown may be variously modified and altered and the invention embodied in other forms of structure without departing from the spirit thereof. Thus by way of example, instead of providing the inner and outer walls of sheet metal piling bars as in the one construction shown or of wood piling as in the other, one wall, 10 as for instance the outer wall, may be formed of metal as in the one construction and the other wall of wood as in the other construction. Furthermore, the invention, as to certain phases thereof, may be embodied in a structure in which either or both of the wall-forming portions thereof are not driven into the ground but merely 15 rest thereon, in which case such portions would be provided as preformed units comprising coverings of sheets, or bars of wood or metal arranged side by side, lowered, instead of driven, 20 to position.

What I claim as new, and desire to secure by Letters Patent, is:

1. A structure of the character set forth, comprising walls spaced apart, and tension means for preventing spreading of said walls comprising members located at intervals along said walls and each extending crosswise thereof from one to the other of said walls, said members having 30 swinging connection with one of said walls, about substantially vertical axes.

2. A structure of the character set forth, comprising walls spaced apart, and tension means for preventing spreading of said walls comprising rigid members located at intervals along said walls and each extending crosswise thereof from one to the other of said walls, said members having 40 sliding interlocking connection with said walls.

3. A structure of the character set forth, comprising walls spaced apart, and tension means for preventing spreading of said walls comprising rigid members located at intervals along said walls and each extending crosswise thereof from one to the other of said walls, said members having 45 sliding and swinging connection with said walls.

4. A structure of the character set forth, comprising walls spaced apart, and tension means for preventing spreading of said walls comprising frame members located at intervals along said walls and each extending crosswise thereof from one to the other of said walls, said walls and 50 means having relatively slideable interlocking operating portions whereby said walls and means are adapted to be assembled by relative longitudinal movement and in the assembled positions of said parts relative lateral movement thereof is prevented.

5. A structure of the character set forth, comprising walls spaced apart and formed at inter-

vals with sections having lateral substantially vertical flanges, and tension means for preventing spreading of said walls comprising members located at said sections and each extending crosswise of said walls from one to the other of said walls, certain of the flanges of said sections forming portions of said walls and the other flange portions thereof and said members having relatively slideable interlocking cooperating portions whereby said means and sections are adapted to 10 be assembled by relative longitudinal movement and in the assembled positions of said parts relative lateral movement thereof is prevented.

6. A structure of the character set forth comprising walls spaced apart and formed at intervals with sections having lateral substantially vertical flanges, and tension means for preventing spreading of said walls comprising members located at said sections and each extending crosswise of said walls from one to the other of said 15 walls, certain of said flanges forming portions of said walls and the other flange portions thereof and said members having relatively slideable interlocking and swingable cooperating portions whereby said means and sections are adapted to 20 be assembled by relative longitudinal movement and in the assembled positions of said parts relative lateral movement thereof is prevented and said means are adapted to be swung on said sections of one of said walls, about substantially 25 vertical axes.

7. A structure of the character set forth, comprising walls spaced apart and each formed of a series of preformed frames and coverings therefor, and tension members for preventing spreading of said walls extending crosswise thereof and operatively connected at their ends with said frames.

8. A structure of the character set forth, comprising walls spaced apart and formed of frames 40 and coverings therefor, and bars having flanges disposed between said frames and slidably interlocking with the ends of said frames, and tension members for preventing spreading of said walls extending crosswise thereof and slidably interlocking at their ends with said bars.

9. A structure of the character set forth, comprising walls spaced part and formed of piling sections, frames extending along said piling sections and piling sections having flanges disposed 50 between groups of said first-named piling sections and slidably interlocking at said flanges with the ends of said frames, and tension members for preventing spreading of said walls extending crosswise thereof and slidably interlocking at their ends with said second-named piling sections.

10. A structure of the character set forth, comprising walls spaced apart and formed of frames and coverings therefor and bars having flanges 60 disposed between said frames and slidably interlocking with the ends of said frames, and tension means for preventing spreading of said walls extending crosswise thereof and operatively connected with said walls.

WALLACE W. SMITH.
